UNITED STATES PATENT OFFICE.

LOUIS J. VIEHMANN, OF EAST ELMHURST, NEW YORK, ASSIGNOR TO TEEPE-WHITNEY CORP., OF NEW YORK, N. Y., A CORPORATION OF NEW YORK.

TABLE.

Application filed March 11, 1927. Serial No. 174,590.

This invention relates to extension tables.

One of the objects of the present invention is to provide a table of improved construction having top sections which may be moved 5 with respect to each other to increase or decrease the top area of the table.

Another object of the invention is to provide a table having top sections which provide working surfaces of comparatively 10 different characteristics affording a more serviceable means for carrying out culinary operations.

Another object of the invention is the provision of a table of the indicated character 15 having relatively movable top sections which may be brought to an extended relationship to increase the top area of the table, and which may be brought to non-extended relationship in which one top section will fit 20 within a recess in the under side of the other top section.

The nature of the invention and its distinguishing features and advantages will appear when the following specification is read 25 in connection with the accompanying drawing, in which—

Figure 1 is a vertical transverse sectional view through the table showing the top sections thereof in a non-extended relationship.

Fig. 2 is a vertical transverse sectional view, the section being taken on the line 2—2 of Fig. 4, and showing the top sections thereof in an extended relationship, and one of the sections being shown in dotted lines swung 35 up.

Fig. 3 is a plan view illustrating an extended relationship of the top sections, one of which is shown in dot and dash lines in one of its positions, and in full lines in its 40 other position.

Fig. 4 is a sectional view taken on the line 4—4 of Fig. 2.

Referring now to the drawings, it will be apparent that the table includes a supporting structure or frame 10 comprising legs 11 which are connected together at their upper ends by side members 12 and end members 13. The side members 12 are connected together by a transverse member 14 45 to add rigidity. A drawer 15 is supported for sliding movement on transverse members 16 connected with the side members 12. A top section 17 is provided, which is the main top section. A second top section 18 is pro-

vided and serves as a supplemental top section. The top section 17 is formed of metal coated with suitable vitreous material such as enamel, porcelain ware, or the like to provide a highly glazed surface. The top section 17 is formed with a depending marginal flange 19 having an inturned portion 20. A lamination of wood or equivalent material 21 and strip members 22 are held in place by the flange 19 and its inturned portion 20. This arrangement provides a recess 23 in the under side of the top section 17. Arranged transversely between the side members 12 and secured thereto at each end of the table is a slide member 24 having a tongue 25 on one side and a groove 26 on 70 the opposite side. Slide members 27 are employed respectively in conjunction with the members 24. Each slide member 27 has a groove 28 in one side thereof to accommodate the tongue 25 of its related member 24. Each 75 slide member 27 moves through one of the side members 12 which is cut out as at 29. The inner ends of the slide members 27 are connected together by a longitudinal member 30. The top section 17 is hingedly connected as at 31 with the outer ends of the slide members 27. It will now be apparent, that the top section 17 is not only slidably mounted on the supporting structure 10 but is also allowed to be swung up and down on 80 the hinges 31. Each of the slide members 27 has a stop 32 which is adapted to encounter the side member 12 through which the members 27 move to limit the outward sliding 85 movement of the members 27. The top section 18 is non-metallic. It is made preferably of wood. The dimensions of the top section 18 are such as to permit the top section 17 to be brought down over the top section 18 when both sections are in their non-extended positions, the top section 18 being disposed in the recess 23 in the under side of the top section 17, as shown most clearly 90 in Fig. 1. This arrangement of the top sections provides a table of ordinary proportion with a comparatively decreased top area. The slide members 33 are employed respectively in conjunction with the members 24. The slide members 33 are secured to the under side of the top section 18 transversely 95 thereof at opposite ends. Each slide member 33 has a tongue 34 which is received in the groove 26 of its related member 24.

Each slide member 33 moves through one of the side members 12 which is cut out as at 35 to accommodate the member. Each slide member 33 has a stop 36 which encounters 5 the side member 12 to limit the outward sliding movement of the top section 18. Each of the end members 13 is cut out as at 37 in order to permit the top section 17 to be brought down far enough so that its upper 10 surface will be substantially flush with the upper surface of the top section 18 when both of the top sections are in the extended relationship. The inner end of each of the members 33 extends beyond the inner edge of the 15 top section 18 as at 38. The inner edge of the top section 17 rests on these extensions 38 when the sections are extended as shown most clearly in Fig. 2. The top section 17 being quite heavy will aid in holding down top section 18 and also prevent it from moving upwardly at the back when downward pressure is put on its outer or front end, when both top sections are fully extended.

When the top sections 17 and 18 are in the 25 non-extended relationship as shown in Fig. 1, and it is desired to make use of the wooden top section 18, the top section 17 is raised slightly on its hinges 31, the top section 18 may then be pulled outwardly to an extended 30 position. The top section 17 may then be let down and one edge will rest on the top section 18. The top section 18 being of wood may be used advantageously for carrying out 35 certain culinary operations such as those requiring use of knives for cutting or slicing articles. When it is desired to get the maximum top area, the top section 17 as well as the top section 18 may be pulled outwardly to the extended position. The sections 17 40 and 18 will then be disposed edge to edge, abutting each other, disposed in substantially the same horizontal plane, as shown most clearly in Fig. 2. The table in this condition will be useful for purposes where a comparatively large top area is desired.

When the top sections are in the non-extended relationship as shown in Fig. 1, they will be superposed; the top section 18 being disposed within the recess 23 in the under 50 side of the top section 17. Thus the top section 17 will be uppermost, and will provide an upper highly glazed surface, making it

easy to be kept clean and serving as a cover for the top section 18.

It is to be understood that the invention 55 is not restricted to the precise arrangement of parts shown and described, as details of construction may be modified and rearranged without departing from the spirit of the invention, the scope of which is limited only 60 by the terms of the appended claims.

I claim:

1. A table comprising a supporting frame, and two relatively movable top sections, slides carried by said frame and hingedly connected 65 at their outer ends with one of said top sections, said hinged section having a depending marginal flange defining a recess adapted to house the other top section, other slides carried by the supporting frame and on which 70 the other top section is fixedly secured, and means whereby the two top sections may be juxtaposed edge to edge in substantially flush relation, said means including cut out portions in the supporting frame adjacent the 75 juxtaposed edges of the top sections providing recesses in which the depending flange at the inner edge of the hinged top section is adapted to be seated.

2. A table comprising a supporting frame, 80 and two relatively movable top sections, slides carried by said frame and hingedly connected at their outer ends with one of said top sections, said hinged section having a depending marginal flange defining a recess adapted to 85 house the other section, other slides carried by the supporting frame on which the other section is fixedly secured, means whereby the two top sections when extended may be juxtaposed edge to edge in substantially flush relation, said means including cut out portions 90 in the supporting frame adjacent the juxtaposed edges of the top sections providing recesses in which the depending flange at the inner edge of the hinged top section is adapted 95 to be seated, said last named slides extending beyond the inner edge of its top section and adapted to be engaged by the said depending flange of the hinged top section, whereby the inner edge of the fixedly secured top section 100 will be held down against upward tilting movement when in extended position.

LOUIS J. VIEHMANN.
